UPHOLSTERY EDGING HAVING AN ANCHOR-
ING FLAP AND METHOD OF PRODUCING
THE SAME

Alexander R. Mitchell, Dedham, Mass.

Application July 24, 1942, Serial No. 452,176

2 Claims. (Cl. 155—184)

This invention relates to improvements in upholstery edging particularly such as are secured to the covering of a spring frame or other means for supporting seat cushions to provide a rib which when covered with the usual finishing fabric will present an ornamental edge and which will serve in holding seat cushions from displacement, and the principal object of the present invention is to provide a unitary construction in which means are provided for anchoring the 10 edging to the frame of a seat in such manner as to prevent rolling up of the edging and to maintain the edging permanently in proper position. The invention also comprises a method of producing an edging of this character.

Usual upholstery edging comprises a substantially cylindrical body having a core around which a layer of felt is wound and provided with lateral contacting extensions with a covering surrounding the body and overlying and underlying the extensions thereof, with means securing the overlying and underlying covering to the fin. The fin is then secured to the spring covering at a distance from the spring frame of the spring construction so that a portion of the body of the edging projects beyond the spring frame. In such old constructions when in use the edging is likely to roll upwardly thereby distorting the finishing covering which overlies it and thus mars the appearance of the article of furniture to which it is applied.

In order to overcome this defect it has been heretofore customary to secure the covering of the edging to the spring covering or to the wire of the frame by manual stitching by a curved needle which is difficult and consumes considerable time. Furthermore such stitching is likely to give way and thereby to permit the edging to roll up in the manner described.

The object of the present invention is to provide a unitary edging which can be economically produced with a minimum amount of labor and which will provide an anchoring flap preferably extending throughout the length of the edging and which when applied to a seat can be readily secured by tacks or otherwise to the frame of the seat in such manner as to maintain the edging permanently in proper position and prevent any distortion of the edging throughout the life of the article of furniture upon which it is employed.

Preferred embodiments of the invention and method of making the same are illustrated in the accompanying drawing, in which,

Fig. 1 is a conventional representation of a seat provided with a spring for supporting the cushion 55

or the springless seat having suitable means replacing the spring;

Fig. 2 is a vertical sectional view illustrating a step in the method of forming a spring covering 5 in which a short section of covering is secured to a longer web of covering adapted to be wrapped upon a suitable body in the manner hereinafter described;

Fig. 3 is a vertical sectional view of one form of fibrous body for the edging showing a core having wrapped around it a layer of felted material with extensions thereof providing the body with a fin adapted to be covered and secured to the spring covering of a furniture seat;

Fig. 4 is a vertical sectional view illustrating the steps in the method for producing one form of edging embodying the invention;

Fig. 5 is a detail view mainly in vertical section showing a portion of the frame of a seat for an article of furniture, the spring frames, one of the springs, the covering therefor, and the upholstery edging embodying the present invention mounted thereon; and,

Fig. 6 is a vertical sectional view showing a 25 modified form of edging embodying the invention.

The method of producing the edging embodying the present invention comprises first forming a body of fibrous material having a suitable fin. A preferred method which is illustrated in Fig. 3 comprises providing a core 1, which may be substantially cylindrical compacted fibrous material or which may be in the form of a rope or otherwise, which is surrounded by a layer of felt 2 to enclose the core 1 and to provide contacting extensions 3 and 4 forming a fin extending laterally from the core with the extension 3 preferably substantially tangential thereto. The next step of the method as

40 illustrated in Fig. 2 consists in placing a web or short base section 5 of suitable fabric, such as burlap, upon a longer web of fabric 6 and securing an overturned edge of the section 5 to the fabric by a line of stitching 7 in such position 45 and in such proportions that the section 5 will extend from the edge of the fin approximately to the vertical plane of the core of the body with the longer web 6 comprising a section 8 adapted to form an anchoring flap and a section 9 of such length as to extend around the body and overlie the fin, as illustrated in Fig. 4. The next step in producing the edging embodying the present invention consists in seaming together at or adjacent to the base of the fin, the fin and the overlying and underlying layers

of fabric by a line of stitching 10 or other suitable means which will maintain the cylindrical form of the body and fin throughout the length thereof. Preferably one or more lines of stitching 11 connect the overlying and underlying layers and the fin of the body therebetween at a suitable distance remote from the line of stitching 10 and the ends of the covering sections 5 and 9 and the fin therebetween are further secured together by overseaming 12 to provide a finished edge.

It will be noted that in this construction the section 8 is only attached to the body by a line of stitching 7 so that the flap 8 is adapted to extend downwardly for attachment to the body of the seat.

Fig. 5 illustrates the manner in which the edging embodying the present invention is secured to a spring covering. In the construction thus illustrated the furniture seat comprises a frame 13 upon which is mounted the lower wire spring frame 14 upon which suitable springs 15 are mounted in the usual manner, the upper ends of the spring being similarly mounted upon an upper wire frame 16. A suitable spring covering 17 of burlap, or other suitable material, is mounted upon and extends across the upper spring frame 16, and thence downwardly and secured at its lower end to the seat frame 13 by tacks or in any other suitable manner. In the construction as shown in Fig. 5 the edging is secured to the spring covering by manual overseaming 18. The anchoring flap 8 is then bent downwardly at substantially right angles to the underlying section 5 of the edging cover and is secured by tacks 19 or other suitable means to the top or side of the seat frame 13.

It may be noted that where the upholstery edging embodying the invention is to be manufactured and sold as a unitary article of manufacture, it is desirable that the edge of the fin shall be finished by overseaming 12, as illustrated in Fig. 4, but that where the edging is to be applied at the place it is manufactured this overseaming may be omitted as the manual overseaming which secures the fin of the edging to the seat covering will suffice also to finish the edge of the fin.

A modified construction is illustrated in Fig. 6 in which the covering for the body and fin of the edging is formed of three webs instead of two. In this construction three webs of burlap or other suitable material are superimposed with their ends 20 flush and are secured together by a line of stitching 21. The covering is then applied to the body and its fin in the manner above described, so that the section 5 will underlie the fin and extend beneath the cylindrical portion of the body. The intermediate web will form the flap 8 and the lower web 9 will extend upwardly around the cylindrical portion of the body and overlie the fin in the manner heretofore described.

It will be noted that in this construction the end portion 22 of the lower flap when seamed to the ends of the superimposed layers as above described and then wrapped around the body, as illustrated in Fig. 6, will provide a concealed seam or blind stitch which will not detract from the appearance of the edging either when sold

as an article of manufacture or when applied to the article of furniture.

It will be understood that the body and its fin may be made of a single piece of felted fibrous material properly fashioned, or in the manner above described, and that the covering for the body and fin may be of any suitable material, and that various other modifications in construction or arrangement of parts may be made within the spirit and scope of the following claims.

Having thus described the invention, what is claimed as new, and desired to be secured by Letters Patent, is:

1. The method of making a complete unitary strip of upholstery edging having a fin adapted to be attached to a yieldable seat member and an anchoring flap adapted to be secured to the rigid frame of an article of furniture which comprises wrapping a thick layer of felted material around a core throughout its length to form a resilient body with laterally extending contacting portions forming a fin, placing a base section of strong covering fabric of such width as to underlie the resilient body and its fin upon a wider strong covering fabric, seaming one edge of said base section to the wider fabric at such distance from the edge of the latter as to provide said wider fabric with an extension of such width as to overlie said body and fin, with an anchoring flap section of any desired width underlying said base section, superimposing the resilient body and fin upon the base section with the body upon the seam, wrapping said extension of covering material around the body and over the fin and securing together the covering sections and the fin therebetween along the base of said fin and remotely therefrom.

2. The method of making a unitary strip of upholstery edging having a fin adapted to be attached to a yieldable seat member and an anchoring flap adapted to be secured to the rigid frame of an article of furniture which comprises forming a compacted substantially cylindrical core of fibrous material, wrapping a layer of felted material around said core throughout its length to form a resilient substantially cylindrical body with laterally extending contacting portions forming a substantially tangential fin, placing a base section of strong covering fabric of such width as to underlie the resilient body and its fin upon a wider web of said fabric, seaming one edge of the base section to the wider web of fabric at such distance from the edge of the latter as to provide said wider fabric with an extension of such width as to overlie said cylindrical body and its fin, with an anchoring section of any desirable width underlying said base section, superimposing the resilient body and fin upon said base section with the body upon said seam, wrapping the extension of covering material around the body and over the fin and stitching together the covering sections and the fin therebetween with parallel lines of stitching respectively along the base of the fin and remote therefrom and overseaming the free edges of said fin and the underlying and overlying coverings thereof.

ALEXANDER R. MITCHELL.
